DESIGN FOR A RAZOR BLADE HOLDER

Daniel E. Leahy, San Francisco, Calif.

Application May 18, 1935, Serial No. 56,897

Term of patent 14 years

To all whom it may concern:

Be it known that I, Daniel E. Leahy, a citizen of the United States of America, residing at San Francisco, county of San Francisco, and State of California, have invented a new, original, and ornamental Design for Razor Blade Holders, of which the following is a specification, reference being had to the accompanying drawing, forming a part thereof.

Fig. 1 is a bottom plan view of a razor blade holder showing my new design,

Fig. 2 is a side elevation, and

Fig. 3 is a top plan view.

I claim:

The ornamental design for a razor blade holder, substantially as shown.

DANIEL E. LEAHY.
